ATTORNEYS.

UNITED STATES PATENT OFFICE.

PERCIVAL W. JONES, OF PAWTUXET, RHODE ISLAND, ASSIGNOR TO ROSENHEIM CO. INC., OF PROVIDENCE, RHODE ISLAND, A CORPORATION OF RHODE ISLAND.

WRIST-WATCH BAND.

Application filed December 15, 1927. Serial No. 240,253.

This invention relates to an improved construction of wrist band for a watch; and the object of this invention is to provide means for widening the loop end of the band 5 to fit watch bails of different widths.

A further object of the invention is the provision of means for forming this loop on the end of the band of a diameter greater than that of the bail pin which passes 10 through it and to mount a bushing in this loop arranged to extend from the ends of the loop to fill in the space of the watch bail which is wider than that of the band loop.

A further object of the invention is the 15 provision of a pair of extension bushings to fit in the band loop and to provide means in the loop for engaging these bushings to retain them in adjusted position.

A still further object of the invention is 20 the forming of flattened portions on the inner ends of these extension bushings to be engaged by a resilient member for retaining these bushings in different adjusted positions.

25 With these and other objects in view, the invention consists of certain novel features of construction, as will be more fully described, and particularly pointed out in the appended claims.

30 In the accompanying drawings:

Fig. 1 is a front view of the watch showing the wrist band of a watch narrower than the space between the watch lugs, the space being filled in by the extension bushings 35 in the loop of the band.

Fig. 2 is a view showing the loop end portion of one end of the band.

Fig. 3 shows the under side of one of the 40 loop ends of the band with a resilient finger formed in the loop.

Fig. 4 is a sectional edge view through line 4-4 of Fig. 2, showing the resilient finger in the loop.

Fig. 5 is a sectional view on line 5-5 of 45 Fig. 3, showing the resilient finger in the loop.

Fig. 6 is a detail showing one of the extension bushings.

Fig. 7 shows an extension bushing fitted 50 into the opposite ends of the loop to abut against the spring finger.

Fig. 8 shows a pair of extension bushings, the combined length of which is greater than the width of the loop and abutting against

each other both being retained by the grip 55 of the spring finger.

Fig. 9 shows the band as mounted between the lugs of a watch the space between which lugs is greater than the width of the band and this space being taken up by the extension bushings of the band loop.

Fig. 10 shows the loop of the band as engaging the bail pin of a watch with the spring finger engaging the bail pin to take up the lost motion in the loop which is 65 formed with a hole of a diameter greater than that of the pin.

Fig. 11 is an enlarged sectional view of the loop through the spring finger.

Fig. 12 is the same as Fig. 11 showing 70 the spring finger as gripping the bail pin.

Fig. 13 shows an extension having flattened portions of different lengths on its inner end.

Fig. 14 is a sectional end view showing 75 these flattened portions.

Fig. 15 shows these extension bushings with flattened portions positioned in the band loop with spring member of the loop engaging these flattened portions to retain 80 the bushings in working position.

It is found in practice that the space between the bail lugs of a wrist watch vary with different watches, and it is therefore found to be of advantage to provide simple 85

and effective means whereby the width of the wrist band at the point where it engages the watch bail may be varied to fit bails of different watches; and to accomplish this in a simple and effective way, I have formed a 90

loop on the end of the band which has a hole of a diameter greater than that of the bail pin, and I have provided a pair of bushings which fit into opposite ends of the loop 95

and extend therefrom to fill in the space between the band and differently spaced bail lugs; also it is found of advantage to provide a spring gripping finger at the loop of the band to engage these extension bushings 100

and retain them in adjusted position in the loop; and the following is a detailed description of the present embodiment of my invention and showing one arrangement whereby these advantageous results may be accomplished:

With reference to the drawings, 10 designates the band which may be formed of a strip of sheet metal having its opposite ends.

rolled into loop form as at 11 for the purpose of receiving the bail pin 12 of the watch 13. Wrist watches are usually provided with a pair of spaced lugs 14 on either side thereof through which this bail pin extends and the space between these lugs varies in different watches. Therefore, in order to provide a band of a given width and render the same adjustable at its attaching ends, I 10 have rolled the end of the band to form the loop 11, the inner diameter of which loop is greater than the diameter of the bail pin 12, and in order to be able to form the bands of uniform width and at the same time cause 15 the same to fit or fill in the space between these lugs 14, I have inserted into this loop a pair of extension bushings 15, the joint length of which is greater than the width of the band or loop so that when these bushings 20 are inserted into the loop to abut end to end as in Fig. 8, they serve to enlarge the width of the loop to fit the next sized space above the width of the band and when a bail of a larger size is required, I draw the bushings 25 outwardly to fill in this greater space between the watch lugs.

It is found in practice of advantage to provide some means for taking up the lost motion between the loop eye and the pin 30 when no bushings are inserted into the loop; and to accomplish this in a simple and effective way, I have split the loop at 16 forming a spring finger 17 which will engage and grip the pin 12, as best illustrated in Fig. 12, 35 to take up the lost motion in this loop. Also, this spring finger may be sprung out to the full diameter of the loop to engage these extension bushings in the loop and grip these bushings and hold them in that position. 40 Then again, this spring finger may be employed as a spacer against which the inner ends of the bushing may abut, as illustrated in Fig. 7; and further this spring finger may be employed to grip flattened portions as 45 at 18 and 19, formed on the inner ends of these bushings 20, as best illustrated in Figs. 13 to 15 inclusive and so grip and retain these bushings in any of their adjusted positions.

50 My improved adjustable bail engaging extension device is extremely simple and practical in its construction and is effective in its operation and by its use the width of the wrist band used where it engages the watch bail may be increased to fit watches having different widths of bails.

The foregoing description is directed solely towards the construction illustrated, but I desire it to be understood that I reserve 60 the privilege of resorting to all the mechanical changes to which the device is susceptible, the invention being defined and limited only by the terms of the appended claims.

I claim:

65 1. A wrist band having a loop formed at

its end to receive the bail pin of the wrist watch, a cylindrical bushing means in said loop of a length to extend beyond the ends of the loop end to widen the same, and a spring finger formed from the loop and arranged 70 to engage said means to hold it in set position.

2. A wrist band having an eye or loop formed at its ends to receive the bail pin of a wrist watch, a pair of endways adjustable 75 bushings in said loop having a combined length greater than the width of the loop, and means formed from the loop for engaging and retaining the bushings in set position. 80

3. A wrist band having a loop formed on its end to receive the bail pin of a wrist watch, the diameter of the hole through the loop being greater than that of the bail pin, and a spring finger formed from said 85 loop portion intermediate its ends for contacting with said bail pin and thereby taking up lost motion between the loop and pin.

4. A wrist band having a loop formed on its end to receive the bail pin of a wrist 90 watch, a spring finger formed from said loop arranged to normally contract the opening through the loop, a pair of extension bushing members extending from both ends of the loop and flattened at their inner ends 95 to be engaged by said spring finger for retaining said bushings in different adjusted positions.

5. The combination with a wrist watch having a bail formed of a pair of spaced 100 lugs with a bail pin extending therethrough, of a wrist band having a loop formed at its end engaging said bail pin and narrower than the space between said lugs, a pair of bushing members about said pin in said 105 loop and extending from its ends to fill the space between said lugs, and means for frictionally gripping and binding said bushings against a portion of said loop in adjusted position. 110

6. The combination with a wrist watch having a bail formed of a pair of spaced lugs with a bail pin extending therethrough, of a wrist band having a loop formed at its end engaging said bail pin and narrower 115 than the space between said lugs, a pair of bushing members in said loop and extending from its ends to fill the space between said lugs, and a spring finger formed integral with said loop arranged to engage said bushings and retain them in adjusted position. 120

7. A band having a loop formed at its end, a pair of bushings in said loop and extending from its ends, and a spring finger formed integral with said loop and arranged to engage said bushings and retain them in position in the loop. 125

8. In combination with a wrist watch having a pair of spaced lugs with aligned openings therein, a wrist watch band having a 130

loop formed at its end of a width less than the distance between said lugs, a pair of bushing members in said loop having an opening therethrough aligning with the 5 openings in said lugs and a single pin passing through the openings in said bushings and into the openings in both of said lugs to pivotally connect the band thereto.

9. In combination with a wrist watch 10 having a pair of spaced lugs with aligned openings therein, a wrist watch band having a loop formed at its end of a width less than the distance between said lugs, said loop having an opening therethrough aligning with the 15 openings in said lugs and a single pin passing through the openings in said loop and into the openings in both of said lugs to pivotally connect the band thereto, and a

spring finger formed from said loop and engaging said pin to prevent lateral movement on said pin. 20

10. In combination with a wrist watch having a pair of spaced lugs with aligned openings therein, a wrist watch band having a loop formed at its end of a width less than the distance between said lugs, a pair of bushing members in said loop having an opening therethrough aligning with the 25 openings in said lugs, a single pin passing through the openings in said bushings and into the openings in both of said lugs to pivotally connect the band thereto, and means for retaining said bushing members in 30 differently adjusted positions in said loop.

In testimony whereof I affix my signature.
PERCIVAL W. JONES.
